UNITED STATES PATENT OFFICE

PAUL B. RENFREW, OF FORT WAYNE, INDIANA, ASSIGNOR TO S. F. BOWSER & COMPANY, INC., OF FORT WAYNE, INDIANA, A CORPORATION OF INDIANA

MACHINE FOR MANUFACTURING FILTER RIBBON

Application filed November 5, 1928. Serial No. 317,343.

My invention relates to apparatus for indenting or embossing metal ribbon which is particularly adapted for a porous laminated filter for use in the purification of oils, although the apparatus may have a general application.

The object of my invention is the provision of an improved and efficient machine for more accurately producing spaced-apart transverse channels in ribbon laminations for a porous laminated filter, the ribbon having spaced ribs to provide passages between the entrance and discharge sides of the filter.

Another object of the invention is the provision of mechanism in a machine for forming filter ribbon of means for adjusting the application of a die wheel on a comparatively long radius to secure more accurate variations of adjustments to enable the machine to produce compressions or indentations in the ribbon which shall be uniform in cross-sectional area throughout their entire length from one edge of the ribbon to the other.

A further object of the invention is the provision of improved ribbon winding mechanism in combination with indenting mechanism.

Other objects of the invention will appear hereinafter, the novel features and combinations being set forth in the appended claim.

In the accompanying drawings—

Fig. 1 is a side elevation of a filter ribbon winding and indenting machine embodying my invention;

Fig. 2 is an end elevation of the machine shown in Fig. 1;

Fig. 3 is a plan view of the machine shown in Figs. 1 and 2; and

Fig. 4 illustrates a fragmentary portion of the filter ribbon with the spaced-apart grooves compressed or indented therein.

In Fig. 1, I have shown two standards 5 and 6 securely mounted on a bed plate 7 at one side thereof. As shown in the plan view in Fig. 3, two additional standards 8 and 9 are mounted on the bed plate 7 at the other side thereof. The standards 5, 6, 8 and 9 support the apparatus for winding and un-

winding the tape and also the apparatus for

indenting the tape or ribbon with the desired spaced-apart cross-channels or grooves.

At the top of the standard 5 is mounted a flat disc reel 10 for carrying on a drum 11 the copper ribbon or tape 12, both surfaces of which are smooth. The drum 11 may be held in place by the thumb nut 13 on the screw-threaded shaft 14 which is secured to the enlarged shaft 15 mounted in the bearing block 16. A cap bearing 17 is mounted above the lower bearing block 16 at the top of the standard 5.

As shown in Figs. 1 and 2, spaces are left on both sides of the cap 17 above the bearing block 16 so that springs 18, 18 may be relied on to resiliently hold the bearing cap 17 against the shaft 15. The springs 18 encircle the adjusting cap screws 19, 19 which extend loosely through openings in the cap 17 and are screw-threaded into openings in the upper surfaces of the bearing block 16. End flanges 20, 21 may be provided to prevent the shaft 15 from moving endwise relatively to the standard 5. It will thus be seen that the disc reel 10 with the convolutions of the ribbon 12 thereon may be mounted on top of the standard 5 to pay out the ribbon 12 in the direction indicated by the arrow 22 in Fig. 1. The unreeling tension may be regulated by means of the cap screws 19, 19.

Secured to the top of the standard 6 is a cap plate 23 on which is rotatably mounted the grooved pulley 24 for receiving and directing downwardly the tape 12, as indicated by the arrow 25 in Fig. 1. The pulley 24 is an idler for the purpose of changing the direction of the ribbon 12 when it is unwound or paid out from the wound up disc form shown in Fig. 1 on the reel 10.

From the idler 24 the ribbon 12 extends downwardly over a portion of the circumferential surface of the base wheel 26, the cylindrical peripheral surface of which is smooth and parallel to its axis of rotation. At the lateral edges of this cylindrical surface of the base wheel flanges are provided corresponding to those of the idler pulley 24 so that the ribbon or tape 12 is in reality directed from the grooved pulley 24 to the grooved base wheel 26.

The tape or ribbon 12 extends from the base wheel 26 to the winding reel 27 in the direction indicated by the arrow 28. The inner end of the wound up disc of ribbon on the reel 10 is secured to the drum 11 as indicated at 29 in Fig. 1, and the other end of the ribbon 12 is secured at 30 to the drum 31 on the reel 27. The drum 31 may be secured to the reel 27 by means of a cap screw 32 on the screw-threaded shaft 33. The shaft 33 is mounted in a bearing in the standard 5 and extends through the latter to the friction clutch 34, as shown in Fig. 2. This friction clutch comprises one element 35 connected rigidly 15 to the shaft 33 and another element 36 which is connected rigidly to the cross-shaft 37 mounted in a bearing in the standard 9. Springs 38 may be relied on to urge the friction transmission pins 39 through openings 20 in the disc 36 against the opposing flat face of the disc 35 to transmit power to the latter.

The source of power for the winding apparatus may be connected to a driven shaft 40 which is mounted in bearings in the standards 6 and 9. This shaft 40 adjacent the standard 6 has secured thereto the grooved base wheel 26 and at the other end of the shaft 40 is mounted the belting indicated at 42 connected to the shaft 37. Therefore, when the driven shaft 40 is rotated, power is transmitted to the friction clutch 34 to effect winding of the reel 27 in a clockwise direction, as viewed in Fig. 1, when the shaft 40 is turned in a clockwise direction.

The sprocket gearing 42 comprises a larger sprocket wheel on the shaft 40 than the sprocket wheel on the shaft 37. Therefore, when the ribbon is first wound on the small drum 31, the reel 27 may be rotated with sufficient speed to keep the ribbon 12 taut along the portion indicated by the arrow 28. As the indented ribbon is wound on the reel 27 and the disc of filter ribbon becomes larger and larger, the tendency would be for the enlarged diameter of the wound up disc of filter ribbon to pull the ribbon 12 faster than it is being paid out from the grooved base wheel 26. The friction clutch 34 may be so adjusted as to permit slipping when the pull 45 on the ribbon 12 exceeds a predetermined limit. The arrangement is therefore such as to effect the winding of the filter ribbon on the reel 27 with uniform tension from the beginning of the winding until the reel 27 is filled. The filter disc thus produced will be composed of convolutions of indented tape wound very tightly and compactly over its entire area extending from the drum 31 to the periphery of the disc element, with the result 55 that the porosity of the completed filter will be uniform throughout the entire area thereof.

Connected to the driven shaft 40 by means 60 of the gears 43 and 44 is a die wheel 45, the peripheral cylindrical surface of which is

provided with cross-grooves or transverse channels 46 leaving raised cross-bars or cross-ribs 47. The die wheel 45 is mounted adjacent the base wheel 26 with just sufficient space intervening to permit the passage of the ribbon 12 and cause the cross-bars 47 of the die wheel 45 to indent the ribbon with corresponding transverse channels or grooves. In Fig. 4, I have illustrated a portion of the tape or ribbon 12 showing the transverse grooves or channels 48 produced by the transverse bars or ribs 47 of the die wheel. The indentations 48 shown in Fig. 4 are spaced apart to correspond with the spacing apart of the cross-bars 47 of the die wheel, thus producing the spaced-apart cross-bars or cross-ribs 49 on one surface of the ribbon or tape.

The ribbon or tape 12 may be of thin metal, such as copper or other metal of sufficient strength to permit tight winding without undue distortion, compression or stretching. The cross-ribs or cross-bars or barriers 49 of Fig. 4 are integral with the body of the ribbon or tape being formed by compressing the metal or indenting it, as illustrated at 48, into spaced-apart channel grooves or indentations. While copper is preferable as the material for the ribbon or tape, it may be of other material according to the nature of the liquid to be filtered; for instance, it may be made of tantalum which is very effective in resisting corrosion. By referring to Fig. 1 it will be seen that the flat face of the tape or ribbon is inward as it is wound tightly over the outer face having the cross-bars 49. It is preferable to have the cross-bars 49 wider than the channels 48 so that when the ribbed ribbon is wound tightly and compactly on the reel 27, the cross-bars 49 will not bend the backs of the grooves 48 on the adjacent convolutions.

The thickness of the metal ribbon or tape and the depth of the grooves or transverse channels may be varied according to conditions and the nature of the liquid to be filtered. It has been found practicable to filter lubricating oil for Diesel engines to use copper ribbons three-eighths of an inch in width and thirty-six ten-thousandths of an inch in thickness with the cross-ribs thereon four ten-thousandths of an inch thick and spaced-apart to form grooves or channels four ten-thousandths of an inch in depth and one-sixteenth of an inch in width, leaving the cross-ribs approximately one-eighth of an inch in width. I do not wish to be limited to these particular dimensions, however, as they are specified merely to illustrate the fact that the porous metal disc formed by winding onto the reel 27 is intended to have such minute passageways or pores between the flat faces of the disc as to require hydraulic pressure to effect flow of oil from the entrance side to the discharge side

of the filter disc element when mounted in filtering apparatus.

The ribbon or tape being of thin metal is wound in substantially concentric layers to 5 form a disc filter element by means of one length of tape or ribbon. The uniformly spaced cross-bars or cross-ribs or abutments form direct tubular passages or pores for the oil to filter through from one side of the 10 filter element to the other. The laminations are spaced by means of the separators or barriers 49 which form the cross-bars or abutments and these in turn co-act with the smooth backs of the convolutions of the tape 15 or ribbon to form the parallel passageways, making the disc filter element porous over its entire area.

Such filter element may be mounted as explained in my co-pending application, Serial 20 No. 289,150, filed June 29, 1928, for an improvement in filters, so that hydraulic pressure is necessary to force the liquid to be filtered through the porous filter element which is formed by winding the indented ribbon 25 on the reel 27.

In order that the porosity of the filter element may be uniform over its entire area, the cross-channels or grooves 48 should be uniform in cross-sectional area from one edge of 30 the ribbon to the other. It is therefore important to provide means for accurately adjusting the spacing of the die wheel from the base wheel and the inclination of the axis of the die wheel relative to the axis of the base 35 wheel. For this purpose I have mounted the shaft 41 carrying the die wheel 45 in sliding bearing blocks 50 and 51. The bearing block 50 is mounted in suitable guideways in the upper portion of the standard 6 and on 40 the under side of the cap plate 23. In a similar manner the bearing block 51 is mounted to have a horizontal sliding movement in suitable guideways at the upper portion of the standard 9 and on the under side of the 45 cap plate 52. By means of an adjusting screw 53 in the upper side of the standard 6 the bearing block 50 may be pushed to the left, as shown in Fig. 1, against the action of the restoring spring 54 shown in Fig. 3. By 50 means of this adjustment the distance between the die wheel 45 and the base wheel 26 may be accurately adjusted according to the thickness of the tape. The distance between the die wheel and the base wheel 26 should 55 be such that when the cross-bars 47 of the die wheel engage the surface of the tape the cross-bars formed on the tape will be at the bottom of the channels 46 of the die wheel. The dimensions are very small and therefore 60 the screw threads on the adjusting screw 53 should be large in number for a given length.

The adjustment for the inclination of the axis of the die wheel is preferably located at a distance from the die wheel equal to many 65 times the width of the die wheel. The shaft

41 is therefore extended to the other side of the bed plate 7 into the bearing block 51 and the adjusting screw 55 applied to the latter as shown in Fig. 3. An abutment screw is 70 shown at 56 for moving the bearing block 51 to the right, as viewed in Fig. 3, when the screw 55 is retracted. When the screw 56 is moved to the left the screw 55 may be used to move the bearing block 51 to the left. While a spring similar to that shown at 54 75 may be used at 56, I prefer to employ an abutment screw so that after the adjustment in inclination is made the bearing block 51 may be positively held in adjusted position, thereby preventing vibrations which 80 may occur on account of slight irregularities in the thickness of the tape while it is being indented by the die wheel. It can readily be seen that when the bearing block 51 is moved in one direction or the other it is varying the inclination of the die wheel 45 on a long radius and consequently the die wheel 85 cross-bars may be accurately located with respect to the base wheel so that the grooves or channels indented into the tape may be 90 uniform in cross-sectional area from one edge of the tape to the other. While the die wheel 45 fits into the base wheel 26 between the spaced-apart peripheral flanges thereof, 95 adjustment in inclination of the die wheel can nevertheless be made, because the necessary adjustments will always be comparatively small. It is highly desirable, however, to secure very accurate and exact adjustments so that when the indented ribbon is wound 100 with a uniform tension, as above explained, the porosity of the completed disc filter element will be uniform over the entire area. In this way the efficiency of the disc filter element is maintained and increased because 105 of the assurance that the passageways or pores will be open from the entrance side to the discharge side of the disc with uniform cross-sectional area and as large a cross-sectional area of each pore within the limits of 110 the type of filter requiring hydraulic pressure for its operation.

Obviously those skilled in the art may make various changes in the details and arrangement of parts without departing from 115 the spirit and scope of the invention as defined by the claim hereto appended and I wish therefore not to be restricted to the precise construction herein disclosed.

Having thus fully disclosed an embodiment of my invention, what I desire to secure by Letters Patent of the United States is:

In a machine for making filter ribbon, the combination of a pair of associated indented wheels having interengaging driving means, one of said wheels comprising a die wheel and having ribbon indenting means formed on its periphery for indenting a surface of the ribbon to form spaced apart grooves extending laterally across the ribbon between 125 130

its opposed side edges, the other of said wheels comprising a roller for pressing the ribbon against the indenting means of the die wheel, an unwinding reel adapted to hold 5 a coil of relatively thin metal ribbon, a winding reel upon which the ribbon is received after passing the indenting wheels, driving means for driving the winding reel and the indenting wheels, said driving means 10 including means for maintaining the ribbon under uniform tension during the indenting and winding operation.

In testimony whereof I have signed my name to this specification on this 19 day of 15 October A. D. 1928.

PAUL B. RENFREW.
